CONTAINER HANDLING MACHINE

George J. Meyer, Milwaukee, Wis., and George L. N. Meyer, Jackson Heights, N. Y., assignors to Geo. J. Meyer Manufacturing Company, Cudahy, Wis., a corporation of Wisconsin

Application April 16, 1931, Serial No. 530,590
Renewed August 15, 1934

14 Claims. (Cl. 259—54)

The invention relates to machines for the handling of containers, such as bottles, cans, jars, and the like.

In the bottling of certain types of carbonated liquids, it is usual to first introduce syrup into the bottles and to then add cold carbonated water without agitation of the syrup, thereby avoiding foaming and loss of gas. The bottles are then crowned as soon as possible after the filling operation. It is desirable to agitate the bottles after crowning to effect mixing of the contents, and it is also desirable to test the bottles for detecting leaks at the crowns and for discovering weak bottles.

15 It is an object of the present invention to provide a high capacity container handling machine of simple and durable construction for effecting the mixing and testing functions in an expeditious manner, and also for subjecting the contents of 20 the sealed containers to a heat treatment as by means of a fluid heating medium.

Another object of the invention is to provide a container handling machine in which the containers are rotated to effect mixing of the contents, and to effect an increase of internal gas pressure where the contents consists of carbonated liquid.

A further object of the invention is to provide a container handling machine in which containers are rotated on rollers for mixing and agitating the contents, and in which simple but effective means are provided for loading the containers onto the rollers and for removing the containers from the rollers.

35 A further object is to provide a container handling machine for heating bottled carbonated beverages to invert the sugar therein, and for placing bottles or other containers at a temperature above the dew point when discharged from 40 the machine, so as to avoid the condensation of moisture on the containers and to facilitate labeling.

The invention further consists in the several features hereinafter set forth and more particularly defined by the annexed claims.

In the accompanying drawings, Figs. 1 and 2 are complementary side elevations of a bottle-handling machine embodying the invention, parts being broken away and parts being shown

50 in section;

Fig. 3 is an end elevation of the machine showing the bottle feeding and rotating means;

Fig. 4 is a fragmentary side elevation of the machine, parts being broken away and parts being shown

55 in section;

Fig. 5 is a fragmentary top plan view of the bottle feeding and rotating means, parts being broken away and parts being shown in section;

Fig. 6 is a sectional elevation taken along the line 6—6 of Fig. 5, and

Fig. 7 is a detail sectional view of the bottle rotating and advancing means, the bottle advancing means being shown at the end of the retracting stroke.

In these drawings, the numeral 10 designates a frame of suitable construction including a horizontally extending bottom tank 11, and a horizontally extending upper chamber 12. At one end of the frame 10 are journalled transversely extending upper and lower shafts 13 and 14, the former carrying a pair of spaced sprocket wheels 15 and the latter carrying a pair of spaced idler wheels 16. At the other end of the frame 10 are journalled a pair of transversely extending upper and lower shafts 17 and 18, the former carrying a pair of spaced idler wheels 19 and the latter carrying a pair of sprocket wheels 20. The pairs of sprocket wheels 15 and 20 and the pairs of idler wheels 16 and 19 are disposed adjacent the opposite side walls of the frame 10. An endless bottle conveyor 21 is disposed within the frame 10 and includes the usual roller-equipped side chains 22 which are carried on the sprocket wheels 15 and 20 and on the idler wheels 16 and 19. The conveyor also includes the usual transversely extending rows of pockets 23 adapted to receive bottles 24. A lower horizontal flight of the conveyor extends between the idler wheels 16 and sprocket wheels 20 and passes through the testing tank 11. An upper horizontal return flight 30 of the conveyor extends between the idler wheels 19 and sprocket wheels 15 and passes through the upper chamber 12. In this chamber the conveyor side chains are supported on angle tracks 25 and at other points the conveyor may be similarly guided in accordance with the usual practice in bottle handling machines. The conveyor includes a vertically descending flight connecting the sprocket wheels 15 and idler wheels 16 and includes an inclined ascending flight at the other end of the machine connecting the sprocket wheels 20 and idler wheels 19. At the descending flight of the conveyor, the crowned bottles are loaded onto the conveyor and discharged therefrom, as hereinafter described.

55 In the present instance, the bottle conveyor is given an intermittent motion in the direction indicated by arrows, and this may be accomplished in any well known manner. In the illustrated embodiment of the invention, the sprocket wheel

shafts 13 and 18 are provided with ratchet wheels 26 and 27, respectively, arranged at opposite sides of the machine. An intermediate portion of the machine frame 10 is provided with spaced uprights 28 in which a horizontally extending shaft 29 is journaled. The shaft 29 carries gear wheels 30 at its opposite ends which have suitable reduction gearing connections with transversely extending shafts 31 and 32, the latter being provided with a clutch 33 and with a pulley 34 which is driven from any suitable source of power, such as an electric motor. A bell crank 35 is journaled on the shaft 13 and its upper arm carries a pawl 36 engageable with the ratchet wheel 26. A connecting rod 37 has one end secured to the upper end of the bell crank 35, and at its other end has a crank connection with one of the gear wheels 30. A lever 38 is journaled on the shaft 18 and carries a pawl 39 engageable with the ratchet wheel 27. A connecting rod 40 has one end secured to the lever 38 and at its other end has a crank connection with the other gear wheel 30. The slowly rotating gear wheels 30 reciprocate the connecting rods 37 and 40 and through the pawl-and-ratchet connections advance the bottle conveyor one step during each revolution of the gear wheels. A brake member 36' acts on the ratchet wheel 26 to hold the conveyor stationary during the pauses in its intermittent travel.

A supplementary frame 41 is secured to that end of the main frame 10 having the descending conveyor flight. One end of the supplementary frame 41 supports a flat topped conveyor chain 42 which receives filled and crowned bottles from a crowner (not shown). The conveyor chain 42 is continuously movable and is driven in any suitable manner. A vertically extending shaft 43 is journaled in the supplementary frame 41 and carries a dog 44 at its upper end, which is provided with adjustable screws 45 drivingly engageable with an upstanding pin 46 secured to a star wheel 47. The star wheel 47 receives bottles from the conveyor chain 42 and has peripheral notches equal in number to the pockets in each transversely extending row of pockets 23 in the bottle conveyor 21. The star wheel 47 is driven continuously, as hereinafter described, and is provided with a blank portion 48 in which no bottles are fed, so that the bottles are advanced in spaced series. The driving dog 44 and star wheel 47 are made readily detachable from the shaft 43 in order to permit the substitution of other star wheels adapted to feed bottles of different diameters. Spring-urged safety gates 49 and 50 are provided adjacent the star wheel for guiding the bottles and for preventing damage to the bottles and mechanism in the event of jamming. The bottles are fed by the star wheel 47 in upright position onto a suitably supported cross conveyor 51 formed of flat top chain which, in the present instance, is continuously driven. The star wheel shaft 43 is driven through a bevel gear connection 52 with a horizontally extending shaft 53 suitably journaled in the supplementary frame 41 and extending parallel to the shafts 29, 31, and 32 on the main frame 10. The shaft 53 carries a sprocket 54 at the end opposite the star wheel 47, and a chain 55 connects this sprocket with a sprocket 56 carried on the continuously driven shaft 31. The cross conveyor 51 is supported on horizontally extending track-forming channel members 57. The end of the cross conveyor adjacent the star wheel 47 passes

about an idler sprocket 58 and the other end passes about a sprocket 59 which is continuously driven from the shaft 53 through suitable gearing connections including a chain drive 60 and a bevel gear drive 60'.

A pivotally mounted frame 61 extends between the cross conveyor 51 and the main frame 10 and includes a cross member 62 arranged below the cross conveyor and secured to side members 62' of channel cross-section. A continuously driven shaft 63 parallel to the shaft 53 is journaled in the frame 61 and in a number of spaced bearings 64 carried on the cross member 62. The frame 61 is thus mounted for swinging movement about the axis of the shaft 63 and the free end of the frame 61 is disposed adjacent the main frame 10 and capable of vertical movement in a direction along the conveyor 21. Transversely extending portions of the frame 61 rest on a pair of spaced angle bars 65, which are pivotally mounted on the frame 61 and have their free end portions disposed laterally adjacent the frame 10. The free end portion of the frame 61 is connected by links 66 with arms 67 fixedly secured to a rock shaft 68 journaled on the frame 61. Coiled springs 69 secured to the frame 10 suspend the free ends of the bars 65 and thus hold the frame 61 in normal position, while permitting its downward movement under abnormal conditions as hereinafter described.

Spaced trough-forming bottle-supporting rollers 70 extend horizontally on the frame 61 and longitudinally of the frame 10 and are journaled at opposite ends in bearings 71 and 72 carried on the frame 61. Each roller carries a helical gear 73, which meshes with a similar gear 74 carried on the shaft 63, the several rollers being rotated in the same direction. The rollers 70 form bottle-receiving troughs therebetween which, at the free ends of the frame 61, register with the intermittently stationary pockets 23 of the conveyor 21. The shaft 63 carries a sprocket 75 at one end which is driven by a chain 76 meshing with a sprocket 77 carried on the shaft 32.

At a point in the cycle of operation when each series of upright bottles on the cross conveyor 51 are in register with the troughs between the rollers 70, the bottles are pushed laterally from the conveyor onto a tilting frame 78 which is pivotally mounted on chains 79 and carries a plurality of pairs of spaced fingers 80 adapted to swing downwardly between the spaced rollers 70 and to tilt the bottles and deposit them onto the rollers. The tilting frame 78 is operated at the proper time in the cycle of operation by a connecting rod 81 which at one end has a safety slip joint connection 82 with a bell crank 83 carried on a pivot member 84. The other arm of the bell crank 83 has an operative connection with a cam groove 85 in one of the gear wheels 30. The tilting frame 78 is urged to its upper position by a coiled spring 79', as seen in Fig. 5. The bottles on the cross conveyor are pushed onto the tilting frame 78 by a pusher bar 86 carried on arms 87 fixedly secured to a rock shaft 88. In the present instance, the tilter member 78 carries spaced partitions 89 which retain the bottles in centered position with respect to the sets of fingers 80 on the tilting frame. One end of the rock shaft 88 carries an arm 90 which, at its free end, has a sleeve 91 surrounding an end portion of a connecting rod 92, the other end of the connecting rod 92 being secured to one arm of a bell crank 93 which is mounted for swinging movement on the pivot

member 84. The other arm of the bell crank 83 has an operative connection with a cam groove 95 formed in one of the gear wheels 30. The pusher bar 86 is urged in pushing direction 5 through a coiled spring 96 surrounding the end of the rod 92 and engaging the sleeve 91, in order to avoid damage to the mechanism in the event of an improperly placed or fallen bottle on the cross conveyor, and the pusher bar is urged in 10 its other direction through a collar 97 secured to the rod 92 and engaging the sleeve 91.

The angle bars 65 form slides on which reciprocating members 98 are slidably guided for longitudinal movement. Each reciprocating slide 15 member 98 carries a pair of spaced bearings 99 and 100 at opposite ends in which transversely extending rock shafts 101 and 102 are respectively journalled for limited rotary movement. The bearings 99 are connected by links 103 to a channel bar 104 extending transversely below the rollers 70. The channel bar 104 carries near its ends upstanding brackets 105 provided with rollers 106 guided in the channel bars 62' of the frame 61. The channel bar 104 is provided with spaced 20 unstanding fingers 107 which extend between the spaced rollers 70 and are adapted to bear against the bottles carried on the rollers for urging them therealong. Arms 108 are fixedly secured to the opposite ends of the rock shaft 102, and an arm 25 109 is fixedly secured to one end of the rock shaft 101 and is joined to the adjacent arm 108 by a link 110. The arm 109 is acted on by a coiled spring 111 urging the rock shafts 101 and 102 in 30 one direction of rotation, as hereinafter described. The rock shaft 101 carries bottle pushing fingers 112 extending between the spaced rollers 70, and the rock shaft 102 is provided with similar fingers 113, which however are bent to provide clearance for the bearings 72. The bearings 72 are 35 provided with upstanding partitions 114 which guide the bottles as they pass from the rollers and into the pockets of the conveyor 21.

The arms 108, carried on the opposite ends of the rock shaft 102, are connected by links 115 45 with the lower ends of an inverted U-shaped bar 116 which is suspended from bearings 117 on the main frame 10. One of the depending legs of the bar 116 is pivotally secured to a rod 118 which has a safety slip joint connection 119 with the lower 50 end of a lever 120 pivotally suspended from a pin 121 which is secured to one of the uprights 28. The lever 120 carries a laterally extending stud 122 which is received in a cam groove 123 formed in one of the gear wheels 30. Through this connection the lever 120 is periodically swung to reciprocate the bottle-pushing fingers disposed between the bottle-supporting rollers 70 and thereby load the bottles into the descending flight of the bottle conveyor 21, as hereinafter described.

60 An unloading device 124 is secured to the frame 10 above the rollers 70 and includes a swinging bottle support 125, which receives the bottles from the conveyor 21 and moves them to upright position for transfer to a cross conveyor 126. The 65 swinging movement of the bottle support 125 is controlled by a link 127 operatively connected with a rock shaft 128. The rock shaft carries an arm 129 connected to the lower arm of the bell crank 35 by a rod 130. The bottle support 125 70 is swung to its upright position by a spring 131 and is returned to its recumbent position through the linkage connections with the bell crank 35. The bottles in the conveyor 21 are pushed onto the bottle support 125 by means of ejectors 132 75 engageable with the crowned heads of the bottles

and pivotally carried on a pair of parallel swinging frames 133 suspended from bearings 134, thus providing a parallel motion for the ejectors. The frames 133 are swung periodically through a link 135 connected to the upper end of a lever 136 5 which is pivotally mounted on the shaft 31. The lever 136 carries a laterally projecting stud 137 which is disposed within a cam groove 138 formed in one of the gear wheels 30.

The clutch 33 on the shaft 32 is controlled 10 through a lever 139 pivotally mounted on a bracket 140. The upper end of the lever 139 is connected to an arm 141 pivotally mounted on a bracket 142. A link 143 connects the arm 141 with a suitable latch mechanism 144 carried on 15 an extension 145 of the frame 10. The clutch is urged to "off" position by a spring 146 acting on the link 143, but is retained in "on" position by the releasable latch mechanism 144. The latch mechanism may also be automatically released 20 through a safety stop device which includes a vertically movable bar 147 carried on the frame 10 and urged to an upper position by a coiled spring 148. The upper end of the bar 147 is engageable with an arm 149 carried on a rock shaft 25 150, which has a link connection 151 with the latch mechanism 144. The lower end of the bar 147 is connected to one of the pivotally mounted bars 65 so that the depression of this bar, incident to incomplete transfer of one or more bottles from the rollers to the conveyor, will result in the tripping of the latch mechanism 144 through the rock shaft 150, thereby stopping the machine. The bar 147 also has a connection with the bottle 30 support 125 of the unloading device so that an incomplete transfer of bottles between the conveyor 21 and the loading device will cause the downward displacement of the bar to effect release of the latch mechanism 144. The extension frame 145 also carries an electric lamp 152 for 40 facilitating the examination of the bottles on the cross conveyor 126.

At the end of the machine opposite the loading and unloading stations, the tank 11 is connected by a pipe 153 to a centrifugal pump 154 driven by 45 an electric motor 155. The pump 154 delivers water through a pipe 156 to a number of trays 157 disposed above the bottles in the upper horizontal flight of the conveyor. The trays 157 have perforated bottoms so that water is discharged onto 50 these bottles to keep them warm for a substantial part of the return travel. The water drains from the bottles onto the slightly sloping bottom of the chamber 13 and runs forwardly in this chamber to a wide inclined trough 158 along which the 55 water descends to the forward end of the tank 11. The warm water in the machine is thus kept in circulation and the bottles are kept warm on both their forward and return travel through the machine. 60

In operation, crowned bottles are discharged in upright position from the crowner onto the continuously moving flat top conveyor 42 which conducts the bottles to the continuously rotating star wheel 41. The bottles are fed by the star wheel 65 in spaced series onto the continuously moving cross conveyor 51 along which the bottles move to a position abreast the tilting frame 78. At this point, the series of upright bottles are pushed onto the tilting frame 78 by the pusher bar 86 70 carried on the rock shaft 88, the latter being operated by previously-described linkage connections with the cam groove 95 in one of the gear wheels 30. The arrival of the bottles at the tilting frame 78 can be timed with respect to the opera- 75

tion of the pusher bar by adjusting the screws 45 on the driving dog 44 to change the angular position of the star wheel 47 on the shaft 43. As soon as the bottles are seated on the tilting frame, the latter is tilted downwardly to the position seen in Fig. 7 to deposit this series of bottles between the rotating rollers 70. This movement of the tilting frame 78 is effected through previously-described linkage connections with the cam groove 85 in one of the gear wheels 30. At the time the tilting frame 70 swings downwardly, the bottle pushing fingers 107 are in their retracted position, and while the tilting frame is in its lower position, the fingers 107 are advanced through their previously-described linkage connections with the cam groove 123 in one of the gear wheels 20 to urge the rotating bottles, necks first, along the rollers. The cycle of operation is then repeated and at the next retracting movement of the bottle pushing fingers 107, 112, and 113, the latter two sets of fingers are depressed as seen in Fig. 7 to pass under previously-deposited bottles. This depression is accomplished by pushing against the arms 108 which rotates the rock shafts 101 and 25 102, the slide members 98 tending to remain stationary for a moment by their frictional engagement with the bars 65, and the rotation of the rock shafts being resisted by the spring 111. When the pushing effort ceases, the spring 111 urges the fingers 112 and 113 to their upper positions so that the previously-deposited bottles on the roller will be advanced along the rollers during the next advancing movement of the fingers. During each advancing movement of the fingers 30 the bottle conveyor 21 is stationary, so that the foremost bottles on the rollers are urged into the adjacent pockets of the conveyor by the fingers 113. As soon as each series of bottles is loaded onto the conveyor, the conveyor is moved one step 35 by previously-described pawl-and-ratchet connections.

The rotation of the bottles by the supporting rollers 70 serves to thoroughly mix the contents of the bottles and also acts to increase the internal gas pressure to some extent. After the bottles 45 are loaded onto the conveyor 21, they pass into the testing tank 11 where the bottles and their contents are warmed by the immersion of the bottles in warm water to further increase the internal gas pressure. Any bottles with leaky 50 crowns are then readily detected by the gas bubbles escaping from the bottles and rising through the warm water in the tank. The leaky bottles are then identified by an attendant in any suitable 55 manner, as by means of rings slipped about their necks, or by other suitable expedients. In the upper horizontal return flight of the conveyor, the bottles are sprayed with warm water from the trays 157 in order to prolong the time during which 60 the bottles are kept at an elevated temperature. This further increases the gas pressure in the bottles so that any weak bottles will be cracked by internal pressure. The bottles are discharged from the descending flight of the conveyor by 65 means of the bottle ejectors 132, which act on the bottles while the conveyor is stationary, these ejectors having previously-described linkage connections with the cam groove 138 in one of the gear wheels 30. The bottles are discharged onto 70 the swinging frame 125 of the unloading device 124 and during the feeding movements of the conveyor this bottle support is swung through previously-described linkage connections with the bell crank 35 to bring the bottles in upright position in readiness to be urged onto the cross con-

veyor 126. The bottles on the cross conveyor are examined by an attendant, who removes any leaky or defective bottles.

The heating of the bottles to a temperature above the dew point, before they are discharged, 5 serves to facilitate the application of labels and the rapid drying of the labels before the bottles are packed in the shipping cases. The prolonged heat treatment to which the bottles are subjected as they are passed through the machine produces 10 an inversion of the sugar present in the syrup.

The bottle conveyor 21 may move continuously, instead of intermittently, without interfering with the bottle-transferring operations.

The machine is capable of operation on various 15 types of containers, such as bottles, cans, and jars. In some instances, the contents of the containers may consist of granulated or powdered material which is mixed by the rotation of the containers. 20

What we claim as new and desire to secure by Letters Patent is:

1. In a container handling machine, the combination of a container support, a conveyor arranged transversely of said support, a tiltably-mounted container receiving member disposed laterally adjacent said conveyor and movable to a position for depositing containers on said support, means for laterally displacing containers from said conveyor on to said tiltably-mounted member, means for tilting said member to a position adjacent said container support, and means for urging containers along said support and away from said tiltably-mounted member. 30

2. In a container handling machine, the combination of a container support, a conveyor arranged transversely adjacent said support, means for feeding containers on to said conveyor in spaced series each including a plurality of containers, a tiltably mounted container receiving member disposed laterally adjacent said conveyor and movable to a position for depositing containers on said support, means for laterally displacing the containers from said conveyor on to said member, means for tilting said member to a 45 position adjacent said container support, and means for urging said containers along said support away from said tiltably-mounted member. 35

3. In a container handling machine, the combination of a container support including spaced members for receiving containers there between, means extending transversely of said container supporting members, container impelling members carried by said means and extending between said container supporting members for urging 55 containers there along, means for reciprocating said first named means in a direction along said container supporting member, and means for withdrawing said impelling members from contact with the containers on the retracted movement of said first named means. 60

4. In a container handling machine, the combination of a support for receiving containers in upright position, a second support, means for transferring the containers from their upright position on said first named support to a reclined position on said second support, a container conveyor, and reciprocatory container impelling means for moving containers from said second support on to said conveyor. 70

5. In a container handling machine, the combination of spaced supporting members between which containers are adapted to rest, a tiltably-mounted member arranged transversely of said container supporting members for receiving con- 75

- 5 tainers in substantially upright position, said tiltably-mounted member including a pair of spaced elements engageable with the side walls of a container and movable to a position between 5 said container supporting members for depositing the containers on said members, means movable between said spaced elements for advancing the container along said container supporting members and means for operating said tiltably-mounted member.
- 10 6. In a container handling machine, the combination of spaced container supporting members, a reciprocatory member disposed adjacent said container supporting members, means for supporting said reciprocatory member, container impelling means carried by said reciprocatory member engageable with a vertical end of a container to advance the container along said container supporting member on the advancing stroke of said reciprocatory member, said container impelling means extending between said spaced container supporting members, and means for withdrawing contact between said container impelling means and said container on the re- 20 tracting stroke of said reciprocatory member.
- 15 7. In a container handling machine, the combination of spaced container supporting members, a reciprocatory slide member adjacent said supporting members, means for supporting said reciprocatory member, container impelling means carried by said reciprocatory member and disposed between said container supporting members and engageable with a vertical end of a container to advance the container along the support 30 when said reciprocatory member travels on its advancing stroke, means for depressing said container impelling means on its retracting stroke, and means for normally urging said container impelling means to its upper position.
- 35 8. In a container handling machine, the combination of a conveyor on which containers are supported in upright position, a starwheel for delivering a spaced series of containers on to said conveyor, a support disposed laterally adjacent said conveyor for receiving containers from said conveyor, means for displacing said containers from said conveyor on to said support, means for operating said starwheel and container pushing means in timed relationship, and means for adjusting the angular position of said starwheel to time the arrival of the series of containers abreast said support.
- 40 9. In a container handling machine, the combination of a conveyor for receiving containers thereon in upright position, means for placing the containers on said conveyor in spaced successive rows, means for moving the containers laterally of said conveyor, a member adapted to receive containers displaced laterally from said first named conveyor, reciprocatory means for advancing containers along said last named member, and a second conveyor for receiving containers which have been displaced laterally of said first named conveyor.
- 45 10. In a container handling machine, the combination of a conveyor for receiving containers thereon in upright position, means for placing the containers on said conveyor in spaced successive rows, means for moving containers laterally of said conveyor, a member adapted to receive containers displaced laterally of said first named conveyor, a second conveyor, and reciprocatory means for shifting containers along said receiving member on to said second conveyor.
- 50 11. In a container handling machine, the combination of a conveyor receiving containers thereon in upright position, a starwheel for transferring containers on to said conveyor and having a notched portion and an inactive portion for feeding said containers in spaced successive rows, means for removing said containers from said conveyor, means for receiving containers displaced from said conveyor, a second conveyor, and means for advancing containers along said last named receiving means on to said second conveyor.
- 55 12. In a container handling machine, the combination of a container support including means to effect the rotation of containers thereon to mix the contents thereof, a container conveyor mounted adjacent said support, container receiving members on said conveyor in intermittent register with one end of said support, means for moving said container along said support and transferring the container to the receiving member, and means for movably mounting the end portion of the support adjacent the conveyor to permit proper alignment of the support with the container receiving means.
- 60 13. In a container handling machine, the combination of a support adapted to receive containers, means to rotate the containers on said support to effect mixing of the contents thereof, a conveyor mounted adjacent one end of said support, container receiving members carried by said conveyor and in intermittent register with said support, means for moving the containers along said support and transferring the containers to the receiving members, and means for pivotally mounting the end of the support remote from the conveyor to permit movement of the edge adjacent the conveyor relative thereto, said container rotating means including driving members disposed coaxially with said pivotal mounting.
- 65 14. In a container handling machine, the combination of a container support, including a plurality of rolls adapted to receive containers with the axes thereof parallel to the axes of the rolls, means to rotate each of the rolls in the same direction, whereby said containers are rotated on their longitudinal axes, and reciprocatory impelling means, operated independently of said rolls to periodically move said containers along said support.

GEORGE J. MEYER.
GEORGE L. N. MEYER.
